CONTAINER ICING MACHINE

William W. Bateman, Mineral Wells, Tex.

Application April 26, 1950, Serial No. 158,161

9 Claims. (Cl. 226—69)

1

This invention relates to ice handling machinery and more particularly to a machine for depositing predetermined quantities of crushed ice into individual containers such as bottle crates.

The invention has for its prime objects, first: to elevate and deposit blocks of ice into a crushing machine for sizing and delivery into a hopper for reception by a quantity measuring chamber. Second: to provide means for moving containers in end to end relationship below the measuring chamber combined with automatically actuated means for discharging into the containers a predetermined quantity of crushed ice from said measuring chamber. Third: to interrupt operation of the ice crushing machine when the receiving hopper is filled to capacity, and fourth: to provide means actuated by the containers themselves for prohibiting further release of ice from the measuring chamber when normal travel of containers is interrupted for any reason.

Other objects will appear as the description proceeds, taken in connection with the accompanying drawings, wherein:

Figure 1 is a front end elevational view of a machine constructed according to the invention.

Figure 2 is a side elevational view.

Figure 3 is a fragmentary view, partly in section, showing the crushing machine control switch and actuating means therefor.

Figure 4 is a fragmentary perspective view showing the container conveying rollers, trip shoe and locking means therefor, including the clutch through which is actuated the ice ejecting plunger.

Figure 5 is a detail view of the clutch, partly in section.

Figure 6 is a perspective view of the driving gear assembly and showing the measuring hopper agitating cam, and

Figure 7 is a fragmentary perspective view of the means for holding the container trip shoe in operative position.

Continuing with a more detailed description of the drawing, reference is made primarily to Figure 1 wherein is shown the vertical frame 10 of the ice elevator which, together with the ice crushing machine embodied in the housing 11, forms the subject matter of an application for Letters Patent Serial No. 151,467, filed by the applicant hereof on March 23, 1950.

The vertical frame 10 extends above the main frame 12 of the container filling machine of the present invention and its upper end terminates

2

adjacent the mouth of the hopper 13 of the ice crushing machine. A chain 14 travels over sprockets arranged on shafts at the top and bottom of the frame 10 and the chain carries lugs, 5 not shown, which engage under successive blocks of ice moving down a chute 15 into the bottom of the frame 10, and which lugs elevate the blocks of ice to the top of the frame 10, to be deposited into the hopper 13 of the ice crushing machine 10 in which they are crushed in the manner described in the co-pending application aforesaid. Described also in said application is the safety catch, consisting of a pair of arms 16, mounted on a transverse shaft 17, supported on the frame 15 10 and which arms extend into the path of ice blocks moving upward in the frame and which are effective to intercept the ice block should it fail to enter the hopper 13 and fall back into the elevator frame. The catch supports the ice block until the next succeeding chain lug is brought into position to engage and move the block on into the hopper 13 for crushing.

The chain 14 is driven through the medium of a motor 16a (Fig. 1) which drives a pulley and 25 belt assembly concealed in the guard housing 17a. The upper pulley of the assembly drives a shaft 18a which in turn operates gears in housing 19a to drive the upper sprocket, not shown, over which the chain 14 operates.

The present invention consists of the frame 12 in which is mounted a measuring hopper 18 having a horizontal flange 19 on two sides thereof at its top and which flange, as better shown in Figure 3, is embraced by a reinforcing frame 20. 30 The flange and frame are drilled on one side to receive the threaded upper ends of a pair of vertically reciprocable rods 21 (Figs. 2, 4 and 6) one of which is disposed adjacent each front leg of the frame 12 to support the hopper 18 on one side. A nut 22 is threaded onto the upper end of each of the two supporting rods 21 (Fig. 2). In support of the opposite side of the hopper 18 is a pair of shorter rods 23 (Figs. 2 and 3), one at each rear corner of the hopper and extending 35 through a hole drilled in the flange and reinforcing frame 20 thereof. A nut 24 is threaded onto the upper end of this rod, which latter is shown as having a threaded portion 25 spaced below its upper end to define an annular shoulder 26 (Fig. 3) on which rests the flange of the hopper 18. The rod extends downwardly through aligned openings in a U-shaped bracket 27 and a coil spring 28 embraces the rod between the legs of the bracket. A nut 29 is threaded 40 onto the larger section 25 of the rod and bears

against the upper end of the coil spring while the lower end of the spring rests upon the lateral lower leg of the bracket 21.

From the foregoing it will be seen that the hopper 18 is supported solely by the rods 21 on one side and the shorter rods 23 on the opposite side and, by virtue of the springs 28 on the rods 23, the hopper is capable of vertical displacement, as caused for example, by crushed ice discharged thereinto from the ice crushing and sizing machine immediately thereabove. The purpose in so mounting the measuring hopper 18 is to provide a means by which to interrupt operation of the ice crushing machine when the hopper 18 is filled with ice. This is accomplished through the medium of a switch 30 (Figs. 2 and 3) against whose contact 31 is moved the lower end of one of the rods 23 when the weight of the crushed ice in the hopper 18 overcomes the resistance of the springs 28. The leads 32 of the switch 30 are in circuit with an electric motor 33 (Fig. 1) which drives the ice crushing machine through belt 34, pulleys 35, (Fig. 2) and meshed gears 36. Thus, when the hopper 18 is filled, its weight will cause the rod 25 to be downwardly displaced and the switch 30 will be actuated thereby to open the circuit to motor 33, de-energizing the same and stopping the ice crushing machine.

The rods 21, in addition to supporting one side of the hopper 18, are also employed as a medium for agitating or shaking the hopper to dislodge ice therein and to insure free flow of the ice therethrough. As will be seen in Figs. 4 and 6, the lower end of each rod 21 is pivotally attached at 34a to an arm 35a, one of which is affixed adjacent each end of a transverse shaft 36a. The ends of shaft 36a are journaled in bearings provided in the ends of base castings 37 of generally the same structural form, one being mounted opposite the other on lower side members 38 of the main frame 12. Referring particularly to Figure 6, it will be seen that one end of shaft 36a extends through a gear housing 39 and carries an arm 40 which is fixed thereon. The end of arm 40 rides on the face of a cam 41, mounted on the end of a shaft 42 which is parallel with shaft 36a. The face of cam 41 has a gradual rise and an abrupt drop 43 which terminates longitudinal reciprocation to each of the rods 21 through the shafts 36a and arms 35a effective to raise the hopper 18 with a gradual movement but allowing the same to drop suddenly to dislodge ice which may adhere to the walls thereof.

The gear housing 39 contains the worm gear 44 which is engaged by the worm 45, the latter being driven by a main driving shaft 46 through coupling 47. The shaft 47 is driven, in turn, by an electric motor 48 (Figs. 1 and 2). In this manner, shaft 42 is driven to actuate the cam 41 mounted thereon to produce the results above described.

Extending through the machine and supported upon angle iron cross members 49 at the front and rear of frame 12 is a platform 50 (Fig. 2), having side flanges 51 to guide containers, not shown, which are moved end to end or side to side, as the case may be, over the platform 50 in a continuous line, such as by any suitable form of endless conveyor on which the crates or containers may be advanced onto the platform 50. The rear end of the platform 50 is in register with a track-way 51a on which containers are conveyed into the machine for filling. The front

end of the platform 50 is in register with a ramp 52 at the front of the machine and which is hinged at 53 so that it may be disposed at any desired angle, either up or down or even on the same plane as the platform, depending upon the direction in which the filled containers are to be moved.

The platform 50 has openings therein in which operate rollers 54. There are two of these rollers, as better shown in Figure 4, and these are mounted on the shaft 42 previously referred to. The purpose of these rollers will be explained after the description of the ice dispensing mechanism which immediately follows:

15 The ice dispensing mechanism by which crushed ice is transferred from the hopper 18 into waiting containers therebelow consists of an elongated measuring chamber 55 below and in communication with the hopper 18, into which 20 crushed ice falls by gravity from the hopper. Arranged for longitudinal sliding movement in the chamber 55 is a pusher plate or hollow plunger 56 which is substantially square in transverse section and is closed except for its rear 25 end to prevent crushed ice from being released from the hopper 18 except when it is in retracted position. Extending through the open rear of the plunger 56 and pivotally attached at 57 to the inner end thereof is a link 58. The link extends out the rear end of the plunger and is pivotally engaged by a pair of parallel arms 59 which are mounted on and depend from a transverse shaft 60, whose ends are journaled in bearings 61 mounted on the opposed vertical members 35 of the frame 12. The shaft 60, however, extends beyond one vertical frame member, as shown in Figure 1, and carries a circular plate 62, which is fixed to the shaft and on the face of the plate is formed a lug 63. Formed also 40 on the plate and in relationship with the lug 63 is a protuberance 64, through which threadedly passes a screw 65. Between the lug and the end of screw 65 extends a lever 66 which is free on the shaft but rotates the latter by alternate 45 engagement with the lug 63 and screw 64, the latter providing an adjustment in the degree of displacement of the lever and consequently limits the extent of oscillation imparted to the shaft 60.

50 It is evident from the foregoing that as the lever 66 is actuated, shaft 60 will be oscillated to reciprocate the plunger 56 through link 58 and the arms 59. Such movement of the plunger 56 will thrust crushed ice from the opposite end 55 of the chamber 55, which is normally closed by a plate 67, hinged at 68 to the top of the chamber, as shown in Figure 2. The crushed ice is thus expelled from the chamber 55 in measured quantities and is received in the containers moving through the machine below the chamber.

60 To operate the lever 66, an arm 69 is pivoted thereto at 70 and extends angularly downward and its lower end is pivoted at 71 (Figs. 2 and 4) to an end of an arm 72, the latter being affixed to an element of the clutch, to be later described, which is mounted on the roller shaft 42. It is apparent therefore that as the shaft 42 rotates, the arm 72 will move in a circular path to reciprocate the longer arm 69 and will therefore 65 oscillate the lever 66 to bring about the results above described.

70 Referring again to the rollers 54 on shaft 42, it will be observed particularly in Figure 4 that a shaft 73 is disposed rearwardly of and parallel 75 with the shaft 42 on which these rollers are

mounted and the ends of this shaft are journalled in the opposed base plates 31. A trip shoe 74 is attached to the shaft 73 through the medium of a pair of fixed arms 75 and this shoe is held normally in the raised position shown in Figure 4 by means of a pin 76 (Fig. 7) reciprocally arranged in a housing 77 which latter is affixed to and extends angularly upward from the horizontal flange of a base casting 37 in the direction of shaft 73. A coil spring 78 is contained in the housing 77 thrusting the pin 76 against a lug 79 which is also affixed to the shaft 73.

The shoe 74 controls passage of containers through the machine and is effective to operate the clutch shown in detail in Figure 5, through which is actuated the crushed ice discharging mechanism just described. The clutch is comprised of the housing 80 which is cast integral with the base castings 37 and contains a clutch collar 81 rotatably retained in the housing 80. A driven element 82, slidably mounted on the shaft 42 is normally urged into engagement with the driving element 83 by means of a coil spring 84 surrounding shaft 42 within the clutch collar 80. A driven element 82, slidably mounted on the shaft 42 is normally urged into engagement with the driving element 83 by means of a coil spring 84 surrounding shaft 42 within the clutch collar 80. One end of the spring bears against a collar 85, threaded onto the end of shaft 42 while the opposite end exerts a force against the inner end of element 82, bringing about engagement thereof with element 83 which latter is secured to shaft 42 by means of a key 86. Such engagement of clutch elements 82 and 83 will result in rotation of the arms 72 and consequent oscillation of the connecting arm 69 to operate the ice ejecting or discharging mechanism earlier described.

In order that the containers themselves will bring about operation of the clutch to control the icing cycle, a cam 87 (Fig. 4) is affixed to the end of the shaft 73 on which the shoe 74 is mounted. This cam has a lobe 88 which is adapted to be received in a recess 89 in a bar 90 each time the shoe 74 is raised to its highest position. The bar 90 is reciprocable and is pivotally connected by means of a pin 91 to the bifurcated head 92 of a clutch engaging plunger 93. A torsion spring 94 is attached to the pivot pin 91 of the bar 90 in such manner that a portion of the spring will underlie the bar to hold the same in operative relationship with the cam 89 while the free ends of the spring are adapted to bear against a protuberance 95 affixed to and extending outward from a base casting 37, in the manner shown. The spring 94 therefore serves the dual purpose of sustaining the bar 90 flexibly with respect to cam 89 and to thrust the plunger 93 inwardly to disengage the driven element 82 from the driving element 83 against the resistance of clutch spring 84.

The plunger 93 enters the clutch housing 80 through a bore made in a boss 96, formed on one side of the housing and the inner end of the plunger is adapted to be moved into a position to bear against the annular cam face 97 (Fig. 5) formed on the clutch collar 81, against the force exerted by the coil spring 84, thus to disengage the clutch elements 82 and 83.

When the bottle crate or container is thrust against the shoe 74, the latter is depressed, causing the shaft 73 to oscillate and thus actuate cam 87. The lobe 88 of the cam being at this moment in engagement with the recess 89 of the retracting bar 90, causes this bar to recede, against the resistance of its torsion spring 94, thereby withdrawing the plunger 93 from engagement with the cam 97 on clutch collar 81. The clutch element 82 will therefore be urged by spring 84 into engagement with the driving ele-

ment 83, whereupon the ice ejecting or discharge mechanism will be set into motion for a period just sufficient for one cycle of operation, that is to say, one cycle for each time the trip 74 is depressed, regardless of how long the trip is held down. This arrangement insures against continued operation of the ice discharging mechanism should the normal travel of containers be interrupted.

It is the primary purpose of the invention to provide apparatus for icing milk bottle crates which are to be loaded onto delivery trucks. It is therefore important that passage of iced containers from the machine be regulated in keeping with the speed at which the containers are loaded onto the delivery trucks.

To accomplish the foregoing, a delaying shoe 98 (Fig. 2) is hinged at 99 to the underside of the ramp 52, down which the iced crates or containers pass from the machine. This shoe is adapted, under the weight of a container, to occupy an opening 100 in the ramp and thus be flush with the top surface thereof. Depression of the shoe by a container moving down the ramp is effective to lock the container trip shoe 74 in raised position, thus to preclude further operation of the filling mechanism until the crate resting on the shoe 98 is removed.

Locking of the trip shoe 74 is accomplished through an arm 101 (Fig. 2) which is pivoted at 102 to a lug 103, affixed to the underside of the shoe 98. The opposite end of arm 101 is pivoted at an end of a lever 104 which, in turn, is pivoted intermediate its ends at 105 to a projection 106 at the front of the machine frame. To the opposite or lower end of lever 104 is pivoted at 107 another arm 108 (see Fig. 4). The arm 108 extends into the machine under the shaft 36a and roller shaft 42 and is pivoted at its inner end to the lower end of a latch 109 which is pivoted to a projection 110 affixed to the inner surface of one of the base castings 37. The latch 109 is notched at its upper end to receive the lower forward edge of the trip shoe 74 in the manner shown in Figure 4, thereby holding the shoe in raised position as long as there is a container resting on the delaying shoe 98.

When the crate or container is moved from the shoe 98, the weight of the arm 101 causes the shoe to rise, resulting in a slight forward displacement of the arm 101. This action causes the lever 104 to rotate slightly, thrusting arm 108 rearwardly thereby displacing the latch 109 with respect to the trip shoe 74. The trip shoe 74 is therefore released for further operation.

In operation, blocks of ice move down chute 15 and are carried by chain 14 and its associated structure into the hopper 13 of the ice crushing machine. The ice crushing machine in housing 11 crushes the blocks of ice and deposits the ice in hopper 18. Since the ice crushing machine is driven by motor 33, the machine will cease operating whenever hopper 13 is filled with crushed ice to the degree necessary to depress the side of hopper 18 yieldably supported on rods 23 and springs 28 and actuate the switch 30. When supply of ice in hopper 18 becomes depleted, the side of hopper 18 supported on rods 23 is raised by springs 23, switch 30 moves to its original position and the ice crushing machine again fills hopper 18. In this manner hopper 18 is always supplied with crushed ice. Plunger 56 is initially in the position shown in Figure 2 and, therefore, the chamber 55 is filled with crushed ice from

hopper 18 said chamber 55 communicates therewith.

The containers or crates to be filled with predetermined quantities of crushed ice are pushed onto trackway 51a and between the side flanges 51 of platform 50 from any suitable form of endless conveyor, not shown, which continuously exerts a force on the crates which urges them to move toward the ramp 52, and as the front side or end of a crate reaches trip 74, it depresses trip 74. Assuming now that shoe 98 is in position shown in Figure 2, lobe 88 of cam 87, which is in recess 89, will pull bar 90 and plunger 93 rearwardly. Plunger 93 will disengage from the cam 97 on clutch collar 81 and the driven element 82 will engage the driving element 83. The linkage comprising arms 72 and 69, lever 66, plate 62 and arms 59 will then be driven by shaft 42 and will cause pusher plunger 56 to move toward the hinged plate 67 which pivots on its hinge 68 when pressed by the ice in chamber 55 which is pushed by plate 56. The ice in chamber 55 will thus be forced from chamber 55 and will pass by gravity into the crates which are passing directly underneath chamber 55. As the front end of the crate passes trip 74 it contacts rollers 54 which are positioned higher than trip 74. As the crate is moved onward by the crates behind it, first its front end and then its rear end will be raised by the rollers 54. This will permit trip 74 to rise which will allow plunger 93 to again engage cam 97 and disengage the elements 82 and 83 of the clutch. The gearing between motor 48 and shaft 42 is chosen to allow plunger 56 to move forward and back during one revolution of shaft 42.

To insure that only one cycle of oscillation of plunger 56 will occur during the passage of any one crate over trip 74, lobe 88 and recess 89 are so shaped that lobe 88 will slip out of recess 89 as trip 74 moves to its lowermost position due to the passage of crate. Torsion spring 94 which yieldingly urges retracting bar 90 toward engagement with lobe 88 will allow downward movement of bar 90. Bar 90 and plunger 93 will therefore be free to move to their original positions. Lobe 88 will ride on the top surface of bar 90 adjacent its free end until trip 74 moves to its original position after the crate passes. It is evident therefore, that plunger 93 will be moved outwardly for only one revolution of shaft 42 upon depression of trip 74 by a crate no matter how long trip 74 is held in its depressed position by the crate.

If crates after their filling are not removed from the machine the foremost crate will descend ramp 52 and depress the shoe 98 which in turn will cause latch 109 to pivot into a position in which it will block downward movement of trip 74. Trip 74 will, therefore, remain in its upper position regardless of the force exerted upon it by the crate which will be next in line. Latch 98 and trip 74 therefore cooperate to prevent further movement of the crates and to prevent further oscillatory motion of plunger 56. This prevents crate from receiving more than the predetermined amount of ice determined by the position of screw 65 on circular plate 62. As is most readily seen in Figures 1 and 2, rollers 54 are positioned in line with flanges 51 at the sides of the platform 50. Platform 50 and flanges 51 are cut out as at a (Fig. 2) to allow rollers 54 to be positioned at the extreme sides of platform 50. This is also true of trip 74 as is shown in Figure 2. Being disposed at the sides of platform 50, rollers 54 and trip 74 will each engage the lower edge of a side of the crate passing over them. This feature pre-

vents the trip 74 from violently contacting the bottles in open bottom crates as it moves back to its upper position under the force exerted by spring 78 since it must of necessity contact the edge of a side of the crate which will prevent upward movement. Trip 74 will therefore operate in the same manner regardless of the type of construction of the crate whether solid bottom or open frame.

It will be noted that shaft 42 rotates continuously, it being driven by motor 48 through gears 44 and 45 and causes the hopper 18 to be shaken continuously due to the coaction of cam 41 and switch arm 40.

Manifestly, the construction as shown and described is capable of some modification and such modification as may be construed to fall within the scope and meaning of the appended claims is also considered to be within the spirit and intent of the invention.

What is claimed is:

1. In an apparatus for delivering predetermined amounts of crushed ice to containers: a hopper having an open lower end adapted to contain crushed ice; a measuring chamber disposed below said open lower end of said hopper and communicating with said hopper through said open lower end, said chamber having a side mounted for pivotal movement; a pusher plate opposite said pivotally mounted side forming the opposite side of said chamber and mounted for oscillatory movement toward and away from said pivotally mounted side; a driven shaft; a mechanical linkage connecting said driven shaft to said pusher plate for oscillating said pusher plate when said driven shaft is rotated; a driving shaft; a clutch between said shafts adapted to connect said driven shaft to said driving shaft; a platform beneath said chamber adapted to support said containers for movement below and past said chamber; a trip disposed in the path of movement of said containers along said platform; a mechanical linkage connecting said trip and said clutch for connecting said shafts when said trip is actuated in its movement along said platform; a ramp connected to said platform; a shoe pivotally disposed adjacent said ramp; a latch adjacent said trip and adapted to prevent actuation of said trip; and a mechanical linkage connecting said shoe and said latch for preventing actuation of said trip when one of said containers is disposed on said ramp.

2. In an apparatus for delivering predetermined amounts of crushed ice to containers: a hopper having an open lower end adapted to contain crushed ice; a measuring chamber disposed below said open lower end of said hopper and communicating with said hopper through said open lower end, said chamber having a side mounted for pivotal movement; a pusher plate opposite said pivotally mounted side forming the opposite side of said chamber and mounted for oscillatory movement toward and away from said pivotally mounted side; a driven shaft; a mechanical linkage connecting said driven shaft to said pusher plate for oscillating said pusher plate when said driven shaft is rotated; a driving shaft; a clutch between said shafts adapted to connect said driven shaft to said driving shaft; a platform beneath said chamber adapted to support said containers for movement below and past said chamber; a trip disposed in the path of movement of said containers along said platform; a mechanical linkage connecting said trip and said clutch for connecting said shafts for

one revolution of said driving shaft when said trip is actuated by one of said containers in its movement along said platform; a ramp connected to one end of said platform; a shoe pivotally disposed adjacent said ramp; a latch adjacent said trip and adapted to prevent actuation of said trip; and a mechanical linkage connecting said shoe and said latch for preventing actuation of said trip when one of said containers is disposed on said ramp.

3. In combination: an ice crushing device driven by an electric motor; a hopper to receive the ice crushed by said device; mounting means for said hopper allowing limited vertical movement of said hopper; a switch for de-energizing said motor operatively associated with said mounting means and actuated when said hopper moves downwardly, a measuring chamber beneath and communicating with said hopper; means for dispensing a predetermined quantity of crushed ice from said chamber; a platform extending beneath said chamber and adapted to support containers for movement beneath and past said chamber; a trip disposed in the path of movement of said containers and operatively associated with said last mentioned means for dispensing a predetermined quantity of ice into one of said containers each time said trip is actuated; a ramp connected to one end of said platform and provided with a pivotally mounted shoe adapted to be actuated by a container on said ramp; a latch adjacent said trip for preventing actuation of said trip; and means connecting said shoe and said latch to prevent actuation of said trip when one of said containers is disposed on said ramp.

4. In a device for dispensing measured amounts of material from a measuring chamber into a container moving on a platform beneath and past said measuring chamber; a rotatable trip shaft mounted transverse of said platform; a trip rigidly secured to said trip shaft and radially spaced therefrom, said trip being adjusted to extend into the path of movement of said container along said platform; spring means biasing said shaft to maintain said trip in the path of movement of said container; a driving shaft and a driven shaft mounted parallel to said trip shaft; a clutch adapted to connect said driving and driven shafts; a plunger operatively associated with said clutch to disconnect said driving and driven shafts in its inner position, said driving and driven shafts being connected when said plunger is in its outer position; a lever pivotally secured to one end of said plunger, said lever being provided with a notch; a cam rigidly secured to said trip shaft and having a lobe adapted to engage in said notch when said trip is actuated by said container, said lobe moving said plunger to its outer position as said trip is actuated and disengaging from said notch to release said lever and said plunger when said trip approaches its fully actuated position; and a spring biasing said lever against said cam and biasing said plunger toward its inner position.

5. The device of claim 4, and a pair of rollers mounted on said driving shaft adjacent opposite sides of and extending above said platform, said trip being biased by said spring to a position extending above said platform, said trip being disposed adjacent a side of said platform to engage a bottom edge of a side of said container when in its actuated position.

6. The device of claim 5, and a second cam on

said driving shaft; a vibrator shaft extending parallel to said driving shaft; a first arm on one end of said vibrator shaft bearing against said second shaft; and a second arm on the other end of said vibrator shaft; and a rod pivotally connected to said second shaft and urging said first arm against said shaft, said second cam imparting oscillatory motion to said rod as said second cam is rotated by said driving shaft.

10. The device of claim 4, and a second cam on said driving shaft; a vibrator shaft extending parallel to said driving shaft; a first arm on one end of said vibrator shaft bearing against said second shaft; and a second arm on the other end of said vibrator shaft; and a rod pivotally connected to said second shaft and urging said first arm against said shaft, said second cam imparting oscillatory motion to said rod as said second cam is rotated by said driving shaft.

15. In an apparatus for delivering predetermined amounts of freely flowing material to containers: a hopper adapted to contain the freely flowing material; means for dispensing a predetermined quantity of the freely flowing material from said hopper; a platform extending below said hopper and adapted to support containers for movement beneath and past said hopper; a trip disposed in the path of movement of said containers; means actuated by said trip operatively associated with dispensing means for causing a single cycle of operation of said dispensing means each time said trip is actuated by a container on said platform, said dispensing means delivering a predetermined quantity of material to a container on the platform each time said trip is actuated, said trip having to return to non-actuated position and again be actuated by another container on said platform before a second cycle of operation of the dispensing means can take place, a ramp connected to one end of said platform; a shoe pivotally disposed adjacent said ramp; a latch adjacent said trip and adapted to prevent actuation of said trip; and a mechanical linkage connecting said shoe and said latch for preventing actuation of said trip when one of said containers is disposed on said ramp.

20. In an apparatus for delivering predetermined amounts of material to containers: a hopper; means for dispensing a predetermined quantity of material from said hopper; a driven shaft; a mechanical linkage connecting said driven shaft to said dispensing means for initiating single cycle operation of said dispensing means when said driven shaft is rotated a single revolution; a driving shaft; a clutch between said shafts adapted to connect said driven shaft to said driving shaft; a platform beneath said hopper adapted to support said containers for movement below and past said hopper; a trip disposed in the path of movement of said containers along said platform; a mechanical linkage connecting said trip and said clutch for connecting said shafts for a single revolution of said driving shaft each time said trip is actuated by one of said containers in its movement along said platform, said trip having to return to its non-actuated position before it can again actuate said clutch to connect said shafts for another single revolution of said driving shaft, a ramp connected to one end of said platform; a shoe pivotally disposed adjacent said ramp; a latch adjacent said trip and adapted to prevent actuation of said trip; and a mechanical linkage connecting said shoe and said latch for preventing actuation

11

of said trip when one of said containers is disposed on said ramp.
